UNITED STATES PATENT OFFICE.

HIRAM MYERS, OF SPRINGFIELD, OHIO, ASSIGNOR TO JOHN A. BLOUNT, OF SAME PLACE.

ROTARY PLOW.

SPECIFICATION forming part of Letters Patent No. 357,963, dated February 15, 1887.

Application filed May 24, 1884. Serial No. 132,721. (No model.)

To all whom it may concern:

Be it known that I, HIRAM MYERS, a citizen of the United States, residing at Springfield, in the county of Clark and State of Ohio, have 5 invented certain new and useful Improvements in Rotary Plows, of which the following is a specification.

My invention relates to rotary plows; and the objects of my invention are, first, to provide 10 a simple, strong, and durable frame adapted to support the revolving cutters firmly in their places without passing the rear of said cutters; second, to provide a simple means for attaching and supporting the guide-wheel; third, to 15 provide for leveling up the frame, thereby adjusting the front and rear cutters to an equal depth of cut; and, fourth, to provide for an additional adjustment of the cranks which serve to raise and lower the cutters.

20 My invention consists in the construction and combination of parts, hereinafter described and claimed.

In the accompanying drawings, which form a part of this specification, Figure 1 is a plan view of a rotary plow embodying my invention, one of the rotary cutters being shown in section. Fig. 2 is a side elevation view of the same. Fig. 3 is a plan view showing the frame in detail. Fig. 4 is a view showing the manner of supporting the tongue. Fig. 5 is a front elevation view of the adjustable crank. Fig. 6 is a sectional view of the same, and Fig. 7 is a plan view of a modified form of frame.

Like parts are indicated by similar letters 35 of reference throughout the several views.

The rotary cutters A and A', of which two are preferably used, are journaled at the front and rear of the carrying-wheels B B. These cutters are set at an angle to the line of draft, 40 and are adapted to turn freely on their axles as the plow is drawn forward to accomplish the plowing in the usual manner.

In order that the cutters may run as freely as possible, and to prevent them from becoming choked or clogged by stalks or weeds, it 45 is desirable that the frame which supports the cutters be so constructed that the cutters will be left perfectly clear at the rear to permit the soil and débris which may be distributed

thereon to be freely discharged from the cutters. To accomplish this I construct the frame in such a manner that it will not at any point pass around the cutter at the rear, the rear or discharge portion of the cutter being thus perfectly clear and open. In constructing the 50 frame in this manner I employ two pieces, a and b, and connect said pieces together by a connecting-piece at right angles to the plane of the cutter and journal the cutter on said connecting-piece. These side pieces, a and b, 55 (see Fig. 3 for detail,) are, at the middle portion, preferably made parallel with the plane of the carrying-wheels. The piece a for a short distance at the front runs parallel with the plane of the cutters and then extends forward 60 parallel with the line of draft to form the draft-connection c. The piece b at the front is bent over and crosses the piece a at right angles to the plane of the cutters, and projects out beyond the piece a sufficiently to form a bearing, 65 d, for the front cutter, A, which is journaled thereon. The pieces a and b at the rear are preferably bent and extended parallel to the plane of the cutters at a distance apart about equal to the length of the hub of the cutters. 70 The rear ends of the frame-pieces a and b, thus extended, are then connected together by a connecting shaft or piece, e, at right angles to the plane of the cutters, said shaft e forming the axle on which is journaled the rear cutter, A'. 75

The journals d and e of the cutters are respectively provided with collars d' and e', preferably welded or otherwise secured on said journals. These collars serve as bearings for 80 the inner ends of the respective cutter-hubs and resist the tendency of the cutter to move longitudinally on the shaft, caused by the forward movement of the plow at an angle to the plane of the cutters. The frame-piece a, where 85 it is crossed by the forward end of piece b, may be formed with a depression to receive said piece b, thus bringing the said piece in the same horizontal plane, a cap, f, being secured over said piece b to hold it in place. 90 The piece a at the rear end is preferably enlarged and provided with a hole large enough to receive the end of the shaft e, which pro- 95

jects through said piece *a*. The piece *b* may be formed with a depression surmounted by a cap, *f'*, to receive the other end of said shaft. The shaft *e* may be secured in the respective side pieces, *a b*, and prevented from turning there by means of pins *h h*, or in any other suitable manner.

In order to bring the draft more directly on the two frame-pieces *a b*, and thus more evenly on the front and rear cutters, A A', I provide a brace-rod, *i*, which extends from the forward end of the piece *a* to the point in the piece *b*, where it turns to cross the piece *a*.

To prevent the plow from running into the land I employ the guide-wheel *C*, which takes the place of the landside on the ordinary drag-plows. In order to obtain a simple, compact, and strong construction, I attach the said guide-wheel *C* directly to the axle *e*. For this purpose the axle *e* is extended through the frame-piece *b* and bent so as to project at right angles to the line of draft. A serrated collar, *k*, is secured rigidly on said projecting portion and an adjustable arm, *l*, by which the guide-wheel *C* is supported, is placed loosely thereon. The upper end of said adjustable arm is provided with a serrated face corresponding to the serrations in the collar *k*. A nut, *m*, on the end of the shaft *e* serves to bind these serrated faces tightly together, and thus hold the arm *k* securely in any position of adjustment.

The rotary cutters, as before stated, are placed in front and rear of the carrying-wheels. Now, in order that the cutters may be regulated to an equal depth of cut and level up the plow, it is essential that means be provided for varying the vertical angle between the draft rod or tongue and the plow-frame. I preferably accomplish this by providing near the front of the frame a supporting-arm, *n*, on which the tongue *D* rests, and extending the tongue back to near the center of the plow-frame, the rear end of the tongue being secured between two vertical standards, *o o*. The standards are secured in a suitable manner to the frame, and are each provided with a corresponding series of holes adapted to receive a bolt, *p*, which extends through the rear end of the tongue.

The tongue *D* is attached to the supporting-arm *n* in such a manner that it is capable of a slight oscillation thereon to compensate for the vertical adjustment of the rear end of the tongue. The supporting-arm *n* is made long enough to permit of a lateral movement of the tongue thereon, the tongue being held against such lateral movement by a brace, *r*, which extends from the side of the tongue to the frame. This brace is secured at its rear end to the frame by a single bolt, *r'*, which passes through a slotted hole, *r''*, in said brace. This slotted hole *r''* permits of a longitudinal movement of the brace *r*, and thus furnishes the means of securing a lateral adjustment of the tongue for the purpose of securing the proper line of draft. To prevent the tongue from being

cramped at the rear end by the lateral adjustment, the tongue should be made to fit loosely between the vertical standards *o o*, or the inner faces of said standards rounded slightly. The hole in the tongue through which the bolt *p* passes should also be slightly elongated.

The cutters may be raised or lowered in passing obstacles or in moving from one place to another by means of the hand-levers *E*. These hand-levers are attached to crank-arms *F F*, which are journaled on a horizontal shaft, *G*, extending transversely across the plow-frame, the carrying-wheels being journaled on bearing-pins in the lower end of said arms in the usual manner.

In order that the cutter may be easily raised while plowing, it is desirable that the cranks which are attached to the hand-levers be as short as possible to obtain the desired leverage. While the plow is in operation it will only be necessary to raise the cutters to the surface of the ground, but when transporting it along the roads the cutters should be raised some inches higher. For this reason I use a crank or cranks adapted to be lengthened or shortened, thereby providing the means for obtaining the increased leverage while the plow is in the field, which may be adjusted to raise the cutters a greater distance from the ground when on the road. To provide for this adjustment I make the crank *F* adjustable, so that it may be lengthened or shortened at will. The main part or body of the crank is made in the nature of a circular disk or wheel, *s*. (See Figs. 5 and 6 for detail.) This wheel *s* is journaled on the shaft, and to it is rigidly secured the hand-lever *E*. Across the face of the wheel I provide a shallow slot or recess adapted to receive a sliding arm, *s'*. The sliding arm carries the stud on which the carrying-wheel *B* is journaled, and is provided with a longitudinal slot, through which the screw-threaded end of the said shaft projects. The bottom of the recess or slot is preferably provided with a series of serrations, as is also the under side of the sliding arm. A nut, *s''*, on the threaded end of the shaft serves to press the sliding arm against the serration, and thus hold it in any position of adjustment. It will be seen that by this construction an auxiliary adjustment may be given to the cutter or cutters when desired to raise said cutters entirely clear of the ground in transporting along the road.

In Fig. 7 I have shown a frame embodying my invention modified to provide for a greater number of cutters. Any suitable number of cutters could be used and the frame modified to suit varying conditions without departing from the spirit of my invention. In this way a gang of plows could be made suitable for use with a traction-engine.

It is obvious that the axle *e* may be made in a single piece with the side piece *a*, said side piece being bent so as to cross the other side piece, *b*, at right angles to the plane of

the cutter without departing from the spirit of my invention.

Having thus described my invention, I claim—

- 5 1. In a rotary plow, the combination, with the rotary cutters, of a frame composed of side pieces connected together at the rear by the axle on which the cutter is journaled, whereby the frame is completed by said axle without 10 passing in the rear of the cutter, substantially as specified.
- 15 2. In a rotary plow, the frame composed of the side pieces, one of which is bent over at the front and crosses the other piece at right angles to the cutter and projects out to form a bearing for the front cutter, the rear end of 20 said piece being extended parallel with the plane of the cutters and connected together by a shaft which forms the axle of the rear cutter, substantially as set forth.
- 25 3. The combination, with the frame composed of side pieces connected together by the axle of the cutter and the rotary cutter journaled on said axle, of the guiding-wheel supported on an arm or bracket, said arm or bracket being secured on the end of said axle, 30 substantially as set forth.
- 35 4. The combination, with the frame connected together at the rear by an axle at right angles to the plane of the cutter and a rotary cutter journaled on said axle, of a guiding-

wheel supported on the end of said axle parallel to the line of draft and at an angle to the plane of the rotary cutter, and means for adjusting said guiding-wheel, substantially as 35 specified.

5. The combination, with the frame connected together at the rear by an axle at right angles to the plane of the cutter and a rotary cutter journaled on said axle, of a guiding- 40 wheel parallel to the line of draft and at an angle to the cutter, said guiding-wheel being supported on the end of said axle by an arm provided with serrations adapted to engage with a serrated collar which is rigidly secured 45 on said axle, and means for tightening said arm against said collar, substantially as set forth.

6. The combination, with the rotary cutters journaled in a horizontal frame at an angle to the line of draft, said frame being adapted 50 to support said cutters without passing in the rear thereof, of the carrying-wheels for supporting said frame and guiding-wheel supported on the same axle that supports the cutter, substantially as shown and described.

In testimony whereof I have hereunto set my hand this 20th day of May, A. D. 1884.

HIRAM MYERS.
